UNITED STATES PATENT OFFICE

LEON T. MART, OF KANSAS CITY, MISSOURI

STEAM SUPERHEATER

Application filed October 9, 1924. Serial No. 742,522.

My invention relates to steam superheaters, with particular reference to superheaters for use with return tubular boilers, or other shell boilers.

5 A purpose of my invention is to support a steam superheater upon the opposite side walls beneath an arch, shown in the drawings as the rear arch of a return tubular boiler.

10 A further purpose is to support an arch of a return tubular boiler upon the horizontally spaced headers of a superheater.

A further purpose is to avoid the use of return bends or castings within the fire zone.

15 A further purpose is to provide a superheater with an advantageous form of interchangeable headers.

A further purpose is to connect horizontally spaced headers having inlet and outlet respectively of a superheater by a plurality of straight tubes through the heating zone and to internally baffle the headers to form a "three-pass" superheater unit in which the steam has to pass three times across the heating space between the inlet and outlet.

20 Further purposes will appear in the specification and in the claims.

I have preferred to illustrate my invention in one main form only (with a slight modification) of the various forms it may take, selecting a form that is inexpensive and effective in operation and which illustrates particularly well the principles involved.

25 Figure 1 is a perspective view illustrating the preferred form of superheater unit.

Figure 2 is a somewhat diagrammatic side elevation showing a return tubular boiler equipped with my superheater.

30 Figure 3 is a fragmentary section of Figure 2, to enlarged scale, taken upon the line 3—3.

Figure 4 is a fragmentary top plan view of Figure 3.

35 Figure 5 is a fragmentary section of Figure 4 taken upon the line 5—5.

Figure 6 is a reduced perspective view of a slightly modified form.

In all figures like numerals refer to like parts.

Describing in illustration and not in limitation and referring to the drawings:—

Prior to my invention steam superheaters for shell boilers have usually extended down through the rear arch—that farther from the stack—and into the relatively intense heat of the zone. Thus placed they have been subjected at the lower end to excessive temperatures with resultant short life, have been inaccessible and moreover have added to the difficulty of installing and maintaining the rear arch.

My invention has been designed primarily to correct these disadvantages though there are features of my invention of broader application than to this locality only.

I rest the superheater by its headers upon the side walls of the uptake flue, avoiding the downward extension referred to and securing a horizontal position for its tubes beneath the arch which forms a roof over them, confining and reflecting the heat upon them. This also enables me to support the rear arch upon the horizontally spaced headers of the superheater. The heating tubes are out of the way, not subject to the too intense heat of the fire zone, and readily accessible for inspection or renewal. Thus installed the superheater makes it much easier to install and to maintain the rear arch.

The superheater unit comprises horizontally spaced headers 6 and 6' preferably alike and interchangeable. They are connected by straight tubes 7, and each is provided with a flanged opening 8 for steam connection, the inlet for the piping shown being upon one side and the outlet upon the other of the top of the unit formed, the inlet in one header and the outlet in the other.

The headers, which may be of cast metal, are shown as partitioned, as at 9 to make the

unit "three pass," that is to cause the steam to pass at high velocity three times through the heating zone of the (rear) flue 10.

In Figure 6 there is a slight modification 5 in that inlet and outlet are from the same header. There is one partition in this header but none in the other, so as to make this a "two pass" unit. It could, of course, readily be made a "four pass" unit. The unit is 10 otherwise used in the same way as that shown in Figures 1 to 5.

Figures 2 to 5 show the invention as part 15 of the equipment of a return tubular boiler. The boiler 11 is shown provided with typical equipment; fire door 12, grate 13, ash-pit 14, outside heating flue 15, rear uptake 10, fire tubes 16, stack uptake 17, stack 18, and main steam pipe 19.

The superheater unit horizontally spans 20 the rear flue 10 slightly beneath the flue cover or rear arch 20, one header, as 6, resting horizontally along the side wall 21 of the flue 10 and having flange connection at 22 with the steam pipe 19 from the boiler, and the 25 other header, as 6', resting upon the opposite side wall 23 of the flue and discharging at any convenient point 24 into the superheated steam supply line 25. The superheating surfaces are provided by the tubes 7 between the 30 headers.

The rear arch 20 is shown as comprising 35 bricks or tiles 26 which are supported by transverse angles 27 and T 28 which angles and T are in turn supported at their ends by resting on the respective headers 6 and 6'.

It will be noted that all cast portions of 40 the unit are placed outside the intense heat of the flue, the heating surface being straight lengths of worked metal in the form of the pipes between the headers. This is an 45 obvious advantage as they can stand intense heat well.

It will further be noted that the covered 45 arch reflects heat upon the tubes which carry the steam so that without necessity for excessive heat at any point it is possible to obtain very uniform heat upon the bottom, top and sides of the tubes.

Steam materially expands during its passage 50 through the superheater unit so that when the header units are alike the discharge velocity is considerably greater than the velocity of intake. For this reason it may sometimes be deemed preferable to forego the advantage of having the headers alike, proportioning the headers and connecting pipes to secure a more uniform velocity 55 throughout the unit.

Likewise it may sometimes be deemed preferable 60 to forego the advantage of the "three pass" arrangement obtained by providing a partition 9 in each header, and in this event these partitions may be dispensed with. While the "three pass" arrangement is desirable 65 in that it gives more intense super-

heating it has also the disadvantage of giving more loss in pressure through the unit which under some conditions may make the single pass arrangement preferable.

In view of my invention and disclosure 70 variations and modifications to meet individual whim or particular need to secure all or a part of the benefit of my invention are likely to become evident to others skilled in the art and I therefore claim all such in so far as they fall within the reasonable spirit and scope of my invention. 75

Having thus described my invention, what I claim as new and desire to secure by Letters Patent is:—

1. In a steam superheater and boiler unit, 80 a fire tubular boiler, side walls forming a flue leading to the boiler tubes, a superheater comprising steam headers supported upon the side walls and steam tubes connected with the headers across the upper part of the flue, and roofing for the flue above the steam tubes and close to them.

2. In a steam superheater and boiler unit, 85 a fire tubular boiler, side walls forming a flue leading to the boiler tubes, a superheater comprising steam headers supported upon the side walls and steam tubes connected with the headers across the upper part of the flue, and roofing for the flue supported upon the headers and raised above the tubes to provide passage for flue gases about the steam tubes.

3. In a steam superheater and boiler unit, 90 a hot flue having opposing walls, a pair of horizontally spaced steam headers in line with the walls, having the length of the headers horizontal and the long sides of the headers forming the tops and bottoms of the headers, pipes making counterconnection across the flue between the headers, an arch supported from the headers free from the pipes, steam inlet and outlet connection to the headers and a fire tube boiler arranged with its tubes in the immediate path of the 95 hot gases passing the steam tubes.

4. In the equipment for a return tubular boiler, 100 a flue at one end of the boiler opening into the tubes thereof and having opposing walls, a header upon each wall, pipes in the flue making a conduit unit with the headers, cover supports carried by the headers, a cover upon the supports free from the pipes, a steam inlet at one end of the unit and a steam 105 outlet at the other end.

5. In a superheater for return tubular boilers, 110 a flue at one end of the boiler, opening into the tubes thereof and having opposite walls, a header upon each wall, a plurality of rows of pipes across from header to header and staggered, one row with respect to the other, arch-supports resting upon the headers above the pipes and an arch upon the supports giving room for circulation between 115 and about the pipes.

6. A pair of sidewalls, steam superheater
headers supported upon the sidewalls and
having the lengths of the headers horizontal,
pipes connecting the headers, flanged sup-
5 ports extending across the space between the
walls and resting at their ends upon the head-
ers and roofing for the space above the head-
ers resting upon the flanges of the supports
and giving room for circulation of hot gases
10 between the pipes and the roofing.
